(57) **CLAIM**

The ornamental design for a consumables container, as shown and described.

DESCRIPTION

FIG. 1 is a perspective view with tear strip in place of the consumables container of the present invention;

FIG. 2 is a side view in elevation with tear strip removed, revealing a removable cap, of the consumables container of FIG. 1, all side views with tear strip removed being identical;

FIG. 3 is a top plan view of the consumables container of FIG. 2;

FIG. 4 is a bottom plan view of the consumables container of FIG. 1;

FIG. 5 is an exploded view with cap removed of the consumables container of the present invention; and,

FIG. 6 is a plan view of the bottom of the cap of the consumables container of FIG. 5.

The broken line showing in FIG. 1 represents a tear line.
